[57] CLAIM

The ornamental design for a rear cup holder armrest, as shown and described.

DESCRIPTION

FIG. 1 is a perspective view of a rear cup holder armrest showing my new design, the chair and armrest shown in broken lines for illustrative purposes only and forming no part of the claim;

FIG. 2 is a side view thereof;

FIG. 3 is a front perspective view thereof;

FIG. 4 is a rear perspective view thereof;

FIG. 5 is a top plan view thereof;

FIG. 6 is a bottom plan view thereof;

FIG. 7 is a side elevational view of an alternate embodiment of FIG. 1;

FIG. 8 is a front perspective view of FIG. 7;

FIG. 9 is a rear perspective view of FIG. 7;

FIG. 10 is a top plan view of FIG. 7; and,

FIG. 11 is a bottom plan view of FIG. 7.

Fig. 1
